ELASTIC FLUID ENGINE

Samuel Lippincott Griswold Knox,
New York, N. Y.

Application February 16, 1945, Serial No. 578,160

7 Claims. (Cl. 121—101)

1

This invention relates to improvements in elastic fluid engines, and more particularly to reciprocating engines operated by a compressed elastic fluid such as steam in which the functions of the usual valves for controlling steam distribution are performed by the piston which is given elliptical motion in its cylinder.

In conventional reciprocating engines, distribution of steam to the cylinder is controlled by valves operating with "angles of advance" relative to piston, thereby to admit steam to the cylinder and thereafter to effect steam cut-off so that the expansion of the steam will be translated into useful mechanical work. The present invention has for its principal object the simplification of steam engine design and operation through the provision of an engine which is valveless in the sense that it has no valve, separate from the piston, for controlling steam distribution, and in which the functions of a valve in effecting distribution are performed by the piston itself. More specifically, the present invention provides a reciprocating engine in which the piston is given elliptical motion and wherein such motion is utilized, in conjunction with ported skirts on the piston and ported sleeves which are interposed between the piston and its cylinder, to effect the necessary steam distribution for either direction of engine operation. According to a further feature of the invention, the ported sleeves aforesaid are so constructed and arranged as to be displaceable relatively to each other and to the piston for the purpose of controlling the direction of engine operation and also to regulate steam cut-off.

Other objects will be in part obvious and in part hereinafter pointed out in connection with the following analysis of this invention wherein is illustrated an embodiment of the invention in detail.

In the drawings—

Fig. 1 is a part sectioned elevation of a two-cylinder engine according to the invention taken generally on line 1—1 of Fig. 2, which shows a typical engine arrangement of cylinder block, cross-head, connecting rod and crank shaft, and which moreover illustrates in detail the sleeve displacing mechanism of the present invention.

Fig. 2 is a section through one cylinder of the engine taken on line 2—2 of Fig. 1, showing the piston in its head-end dead-center position, and further illustrating sleeve mounting and arrangement relative to piston according to the invention.

Fig. 3 is a section taken on line 3—3 of Fig. 1.

2

Figs. 4, 4a, 4b, 4c, 4d, 4e are developed views of a portion of the piston and sleeves as the latter are seen from the interior of the piston, showing progressive positions of piston ports to sleeve ports through one-half rotation of the crank shaft, the displacement of the sleeves corresponding to counterclockwise rotation of the crank shaft as viewed in Fig. 2.

Fig. 5 is a view corresponding to Fig. 4, showing 10 opposite displacement of the sleeves to effect opposite operation of the engine.

As with other engines, an engine according to the present invention may be constructed with a single cylinder or with multiple cylinders. However, since a two-cylinder double acting arrangement represents the simplest self-starting construction, the following description will be based on this type. It will be noted also that the invention is not limited to the vertical engine arrangement as illustrated.

Referring in detail to the drawings wherein like reference characters designate like parts throughout the several views, with the letters H and C designating head and crank end parts, respectively, and thus differentiating opposite, similarly numbered parts, the two-cylinder engine shown comprises a cylinder block 6 having two elongated cylinder spaces, in each of which operates a piston 7 which, as shown in Fig. 2, is formed 15 with a long skirt 7H at its head end and a similar skirt 7C at its crank end. A piston rod 8 connects the piston to the cross head 9 and the latter is connected by connecting rod 10 to the crank shaft 11 turning in bearings generally as shown. 20 The aforesaid engine parts are arranged as usual to convert the expansive force of the steam to rotative force on the crank shaft 11. In Fig. 2, reference characters 12, 13 designate, respectively, coaxially related head and crank end 25 sleeves which are interposed between the piston and its cylinder, the sleeves having their adjacent ends lapped as shown and being mounted in the cylinder block for angular (circumferential) displacement relative to each other and hence to the piston 7.

Oscillating motion in addition to the usual translation of the piston is obtained by incorporating bevel gear teeth 14 built into the connecting rod 10 which mesh with the teeth of a 30 bevel pinion sector 15 which is affixed to the lower end of the piston rod 8. The teeth 14, 15 are located between the cross head and crank pin of the connecting rod 10, so that as the crank shaft rotates, motion of the connecting rod in a plane 35 transverse to vertical translation will produce

partial rotation of the bevel sector 15 and therefore of the piston rod 8 and piston 7. This oscillating rotational movement, combined with the normal reciprocation of the piston rod, produces piston motion such that any point of the piston surface moves in a substantially elliptical path.

Steam is supplied to the engine from any suitable source through a pipe 16, a poppet valve 17 controlling passage of steam from the pipe to lower and upper chests 18C, 18H which communicate through branch pipes 18a, 18b (Fig. 1). The chests open respectively into annular head and crank end steam passages 19H, 19C formed in the cylinder wall. The latter passages communicate through openings (not shown) provided in the cylinder wall sides with a plurality of head and crank end admission ports 20H, 20C, which are formed in the sleeves 12, 13, respectively, and are arranged in circular series therein. The piston skirts are also provided with a like number of head and crank end ports 21H, 21C, respectively, similarly arranged in circular series and functioning to pass steam through the piston skirts to the interior of the piston. The aforesaid elliptical motion of the piston is utilized to open and close the piston ports to the admission ports 20H, 20C of the sleeves 12, 13, respectively. These sleeves are positioned in a manner to be described so that admission of steam occurs just before piston dead-center and that the point of cut-off is regulated by the angular position of the sleeves relative to each other and to the piston.

In addition to the steam admission ports 20H, 20C provided therein, the sleeves 12, 13 are each provided with two supplementary admission ports, the supplementary ports 22H of sleeve 12 and the like ports 22C of sleeve 13 being more or less symmetrically disposed on opposite sides of the sleeve center lines as indicated in Figs. 4 and 5. The function of the supplementary ports is to allow a small amount of steam to pass to the engine after the piston closes the main sleeve admission ports whereby the desirable delayed cut-off features disclosed and claimed in my prior Patent No. 2,091,996, dated September 7, 1937, are obtained and the engine will be self-starting in spite of early cut-off. The supplementary ports 22H, 22C are of restricted size, as shown, and are thus unable to pass any substantial amount of steam when the engine is running at normal speed.

The cylinders are exhausted by conventional uniflow ports 23H, 23C in the upper and lower ends of the sleeves 12, 13, respectively, which are controlled by the ends of the piston skirts, and which open into the exhaust jacket space 24. In order to delay the start of compression, advantage is taken of the piston ports 21H, 21C and the elliptical travel of the piston by providing a plurality of auxiliary exhaust ports 25H, 25C in the head and crank end sleeves 12, 13. Both the uniflow exhaust and the auxiliary exhaust ports are arranged in circular series, generally as shown. While not necessary to engine operation, the inclusion of the auxiliary exhaust ports as permitted by the elliptical motion of the piston results in improved engine operation over the conventional uniflow design.

Provision is made for shifting the sleeves, 12, 13, circumferentially a given amount and in opposite direction, thus to control the direction of engine operation, and also to vary the cut-off. Referring to Figs. 1-3, the chests 18H, 18C are

shown to be formed as parts of a unitary casting secured to the cylinder block side. The casting in its intermediate portion provides a bearing for a tubular sleeve 27 mounted for both rotary and reciprocating motion, through the bore of which extends valve stem 17a of poppet valve 17. The tubular stem 27 is keyed to a bevel segment 28 meshing with a bevel pinion 29 journaled for rotation about a fixed axis having bearing in the chest casting. The bevel pinion is fast on a cylindrical pinion 30 (Fig. 3), the teeth of which mesh with upper and lower racks 31H, 31C, which are pivotally joined at their ends to studs 32H, 32C affixed to the sleeves 12, 13, respectively. Thus, by reference to Fig. 1, it will be observed that counterclockwise rotation of the bevel pinion 29 incident to leftwise turning of sleeve 27 results in displacement of the upper rack 31H to the left and corresponding displacement of the lower rack 31C to the right. As the racks are affixed to the sleeves, the latter are correspondingly displaced in opposite directions and by a given amount depending on the degree of rotation of sleeve 27.

The tubular sleeve 27 terminates at its upper end in a head 27a, against which a head 17b, formed at the upper end of the poppet stem 17a is secured, whereby lowering movement of the sleeve results in corresponding lowering movement of the stem and opening of the poppet valve 17. The sleeve head carries a yoked clevis 34 between the upper leg ends of which is pivoted one end of a duplex link 35. The other end of the link 35 is pivoted to the lower end of an arm 36, the upper end of the latter being pivotally connected to a swivel 37 turning in a fixed support 38. An operating lever 40 having a handle at its free end is formed integral with the duplex link 35 and carries a pivoted locking handle 41 for a pawl 42, the latter being adapted to ratchet with teeth 43 extending along an arcuate edge formed on an extended portion of the arm 36.

By the above described arrangement, raising movement of operating lever 40 results in lowering movement of both tubular stem 27 and poppet stem 17a, and hence in opening of the poppet valve 17, the linkage system being such that raising movement of the lever results in graduated opening of the valve as required to effect throttling. Locking handle operates through pawl 42 and ratchet 43 to hold the poppet valve to any desired degree of opening. In addition to its raising movement as aforesaid, the operating lever is also bodily turnable to each side of a normal central position, the latter movement resulting in turning of the bevel segments 28 and angular displacement of the sleeves 12, 13 in opposite direction as aforesaid. Accordingly, the described arrangement provides a single control for effecting throttling and for determining the direction of engine operation. And, due to the fact that displacement of the sleeves 12, 13 is also employed to vary cut-off, the single control means as aforesaid additionally provides means for varying cut-off through angular displacement of the sleeves.

Figs. 4, 4a, 4b, 4c, 4d, 4e illustrate the progressive positions of the piston ports to sleeve ports through one-half rotation of the crank shaft, and will serve to explain the operation of the engine. In Fig. 4 the piston 7 is shown in its head-end dead-center position, and the sleeves 12, 13 are shown as displaced relatively to each other from their mean or central positions to sleeve positions corresponding to counterclockwise direction of

rotation of the engine as indicated by crank shaft arrow (Fig. 2). With the motion of the piston being such that any point on the piston, and specifically the point P thereon, moves in an elliptical path, the motion of the piston is designated in the said figures by a dot and dash ellipse, and the counterclockwise direction of motion by the applied arrow. For such direction of rotation, the supplementary port 22H to the right of the center line of sleeve 12, and the supplementary port 22C to the left of the center line of sleeve 13 are operative, the alternate set of supplementary ports being inoperative, i. e. at all times covered by the piston.

In Fig. 4 it will be seen that the piston ports 21H have just opened to sleeve ports 20H, with the engine crank on dead-center. No other ports are open except uniflow exhaust ports 23C at the crank or opposite end of the cylinder. Fig. 4a shows a further advanced position with piston ports 21H open to sleeve ports 20H. At the opposite end of the cylinder the main exhaust ports 23C have been closed by the piston skirt 1C. However, at this point of piston travel, the piston ports 21C are starting to open to the auxiliary exhaust ports 25C, thus delaying the start of compression at the crank end of the cylinder.

Fig. 4b shows the approach to the cut-off of steam at the upper or head end of the cylinder, and also that the operative supplementary admission port 22H is admitting a small quantity of steam, thereby delaying cut-off for self-starting. At the crank end of the cylinder, auxiliary exhaust through ports 25C is still taking place. Fig. 4c shows that main cut-off has taken place at the head end of the cylinder except for supplementary admission through small port 22H. At the lower end of the cylinder, auxiliary ports 25C have been covered so that further down movement of the piston effects compression therein. Fig. 4d shows cut-off of the operative supplementary port 22C. Comparison of piston position in Fig. 4d with that shown in Fig. 4b illustrates the difference between the main and supplementary cut-off. Fig. 4e shows the uniflow exhaust ports 23H at the head end of the cylinder open. At the crank end, the piston ports 21C are just approaching sleeve ports 20C so that main admission to the crank end of the cylinder is about to begin.

With the aforesaid views showing successive positions of the piston and sleeve ports through one-half revolution of the crank shaft, by simple reversal they also illustrate successive piston and port positions for the other half of the crank shaft revolution.

Fig. 5 is a view corresponding to Fig. 4 but illustrating displacement of the upper sleeve 12 to the right and of the lower sleeve 13 to the left of their relative position shown in Fig. 4, as required for rotation of the engine in opposite direction. In the view, the motion of the piston is in clockwise direction, with the point P describing the elliptical path shown. Inasmuch as relative position of piston and sleeve ports follows generally that described in connection with Figs. 4-4e, inclusive, with the difference that the piston in Fig. 5 is moving clockwise, no detailed description or repeated illustrations for the opposite direction of rotation and with the sleeves positioned as in Fig. 5 is believed to be necessary.

Without further analysis it will be self-evident from the above description that an engine according to the invention is "valveless" in the sense that it employs no valves separate from the pis-

ton, and that the control and distribution of the steam to the cylinders thereof is obtained through the elliptical motion of the piston, in conjunction with the use of ported piston skirts and ported sleeves which are interposed between the skirted piston and its cylinder. In addition to simplification of steam engine design and operation, the invention further provides an extremely simple yet effective means to vary the point of cut-off through variation in the degree of sleeve displacement relative to piston, and hence a variation of the point at which the piston ports move out of registry with the sleeve admission ports. The invention also provides an exceedingly simple means of reversing the direction of engine operation, which feature is achieved by the simple expedient of displacing the sleeves by a given amount to opposite sides of their normal central position. The invention also makes use of the motion of the piston in delaying the start of compression, as well as to effect delayed cut-off and hence self-starting of the engine.

While the above description refers to the use of ported sleeves by which the desirable variable cutoff and reversing features are in part achieved, such sleeves are not essential to an engine operating as described where the variable cutoff and reversing provisions are not required, and hence may be omitted without departing from the scope and spirit of the present invention. Moreover, although the engine as described has been referred to specifically as a steam engine, it can of course be operated by the pressure of elastic fluids other than steam. Hence, it is to be understood that where steam is used throughout the specification and in the claims, such use is made for convenience only and is intended to designate and embrace all forms of elastic fluids capable of operating engines of the character herein described.

It is also to be understood that the word "elliptical" as used in the foregoing description and in the appended claims to describe the motion or path of travel of the piston is employed for convenience to define its simultaneous reciprocating and rotating movement or travel, which may not follow a true geometric ellipse. Accordingly the expressions "elliptical motion" and "elliptical path" as herein used are to be broadly construed to embrace any and all such motion or travel of the piston as results from its compounded reciprocating and rotative movement.

Moreover as many changes could be made in carrying out the above construction without departing from the scope of the invention, it is intended that all matter contained in the above description or shown in the accompanying drawings shall be interpreted as illustrative and not in a limiting sense.

I claim:

1. In a reciprocating engine, a cylinder, a piston, the cylinder having steam supply and exhaust openings, a sleeve interposed between the piston and the cylinder, the sleeve having admission, supplementary exhaust and main uniflow exhaust ports opening to the cylinder supply and exhaust openings and to the cylinder space, the piston having end skirts provided with ports opening to the interior of the skirted ends thereof, the sleeve and piston ports having a relationship such that the piston ports open and close the interior of the skirted ends of the piston to the steam supply and exhaust openings during motion of the piston in an elliptical path, and

means responsive to the operation of the engine for imparting elliptical motion to the piston.

2. In a reciprocating engine, a cylinder, a piston, the cylinder having steam supply and exhaust openings, a sleeve interposed between the piston and the cylinder, the sleeve having main admission, supplementary admission, supplementary exhaust and main uniflow exhaust ports opening to the cylinder supply and exhaust openings, respectively, and to the cylinder space, the piston having end skirts provided with ports opening to the interior thereof, the sleeve and piston ports being so related and arranged that the piston ports open the interior of the skirted ends of the piston successively to the main and supplementary admission ports and to the exhaust ports of the sleeve upon motion of the piston in an elliptical path, and means responsive to the operation of the engine for imparting elliptical motion to the piston.

3. In a reciprocating double acting engine, a cylinder, a skirted piston, coaxial relatively displaceable sleeves interposed between piston and cylinder, the cylinder having steam supply and exhaust openings, the sleeves and the piston skirts being provided with ports for opening the interior of the skirted ends of the piston to the supply and exhaust openings, respectively, upon motion of the piston in an elliptical path, means responsive to engine operation for imparting elliptical motion to the piston, and means for displacing the sleeves an equal amount in opposite directions whereby to effect control of the direction of engine operation.

4. In a reciprocating double acting engine, a cylinder, a skirted piston, coaxial relatively displaceable sleeves interposed between piston and cylinder, the cylinder having steam supply and exhaust openings, the sleeves and the piston skirts being provided with ports for opening the interior of the skirted ends of the piston to the supply and exhaust openings, respectively, upon motion of the piston in an elliptical path, means responsive to engine operation for imparting elliptical motion to the piston, the relation and arrangement of sleeve ports to piston ports being such that opposite displacement of the sleeves to the sides of a mean position is required to effect engine operation in a given direction, and means for effecting opposite displacement of the sleeve

in either direction thereby to control the direction of engine operation.

5. In a reciprocating engine, a cylinder, a skirted piston, an angularly displaceable sleeve interposed between piston and cylinder, the cylinder having steam supply and exhaust openings, the sleeve and the piston skirts being provided with cooperating ports adapted upon motion of the piston in an elliptical path to control admission of steam to the interior of the skirted ends of the piston and to effect steam cut-off, means responsive to engine operation for imparting elliptical motion to the piston, and means for effecting angular displacement of the sleeve thereby to vary the point of cut-off.

6. In a reciprocating double acting engine, a cylinder, a skirted piston, coaxial sleeves interposed between piston and cylinder and being mounted for relative angular displacement, the cylinder having steam supply and exhaust openings, the sleeve and the piston skirts being provided with cooperating ports adapted upon motion of the piston in an elliptical path to control admission of steam to the interior of the skirted ends of the piston and to effect steam cut-off, means responsive to engine operation for imparting elliptical motion to the piston, and means for effecting relative angular displacement of the sleeves thereby to vary the point of cut-off.

7. In a reciprocating double acting engine, a cylinder, a skirted piston, coaxial sleeves interposed between piston and cylinder and being mounted for relative angular displacement, the cylinder having steam supply and exhaust openings, the sleeve and the piston skirts being provided with cooperating ports adapted upon motion of the piston in an elliptical path to control flow of steam to the interior of the skirted ends of the piston and said ports being arranged so that opposite angular displacement of the sleeves from a central position is required for operation of the engine in one direction and that reverse angular displacement of the sleeves from said central position is required for reverse engine operation, and a single control means selectively operable to effect throttling of steam passing to the engine supply openings and to effect equal and opposite displacement of the sleeves in either direction.

50 SAMUEL LIPPINCOTT GRISWOLD KNOX.
